TUNABLE CAVITY RESONATOR

Ralph J. Bondley, Scotia, N. Y., assignor to General Electric Company, a corporation of New York

Application August 11, 1952, Serial No. 303,794

7 Claims. (Cl. 333—83)

My invention relates to cavity resonators and has particular reference to resonator tuning means.

The resonant circuits for most forms of microwave or ultra-high frequency equipment are cavity resonators whose resonant frequencies are determined by the cavity geometry and the mode of oscillation. For any particular mode of oscillation, the frequency may be changed by altering the cavity size, such as by moving one or more of the walls of the cavity resonator. In relatively low power devices electrical continuity of the movable element is usually maintained by means of sliding plungers or contact fingers. Such sliding contacts, however, are not generally suited for use either at high power or in vacuum since the sliding metal surfaces may be welded to each other. In addition, a poor contact between the sliding members will generally lower the Q or sharpness of tuning of the resonator. In some types of high power vacuum equipment the resonator size is sometimes controlled without using sliding contacts by deforming the resonator walls, or by employing bellows arrangements, but usually with the accompanying disadvantages of limited tuning range, low mechanical durability, or undesired inductance.

It is therefore an object of my invention to provide a simple and improved means for changing the resonant frequency of a cavity resonator by changing the cavity size or geometry.

It is another object of my invention to provide conductive continuity between relatively movable walls or wall portions of a cavity resonator without employing sliding contacts.

It is a further object of my invention to provide means for tuning a cavity resonator which has relatively long life at either high power or in vacuum.

According to my invention, in a cavity resonator which is tuned by moving one of its walls or a portion thereof, the opposite ends of a plurality of thin, flexible metal straps are firmly fixed to the opposing relatively movable resonator surfaces. The straps are narrow and are long in relation to the spacing between the interconnected members so that a central portion of each strap extends in a given direction between the conductive surfaces as a single loop, the curved portion of which shifts or rolls with the displacement of one of the resonator walls or portion thereof. The straps are closely spaced so that the Q or bandwidth of the tunable cavity resonators is maintained essentially the same as a fixed frequency solid wall resonator. Because of the flexibility of the thin conductive straps and the rolling action that occurs when the resonator is tuned, very long life is obtained.

The novel features which I believe to be characteristic of my invention are set forth with particularity in the appended claims. My invention itself, however, together with additional objects and advantages thereof, may best be understood by reference to the following description, taken in connection with the accompanying drawing in which Fig. 1 is a sectional view of a portion of a resonator incorporating my invention; Figs. 2a and 2b are

2

partial views of the apparatus of Fig. 1 illustrating different positions of the movable cavity resonator wall; Fig. 3 is a sectional view of the apparatus of Fig. 1; Fig. 4 is an end view of a rectangular resonator embodying my invention; and Fig. 5 is a sectional side view of another cavity resonator embodying my invention.

Referring now to Fig. 1 a portion of a resonator surrounding a resonant space or cavity 1 is illustrated in which a hollow outer conductor assembly 2 is terminated at one end by an inner conductive cylinder or piston 3 which is coaxial with the outer conductor but spaced therefrom. The face of the piston defines the resonator wall and the cylindrical surface of the piston serves as a guide as explained in the following paragraphs. The back side or end of the concentric conductor assembly beyond the piston 3 is closed by a transverse disk 4 which is secured to the end of the hollow outer conductor assembly 2. A center rod 5 which slides through a central bore in the end disk 4 has its inner ends secured to the piston 3, its external end being available for adjustment of the axial position of the inner cylinder. While electrical contact may be made between the inner and outer conductors if the end disk 3 and adjusting rods 4 are made of metal, no current flows and the resonator tuning is not affected, the end assembly being utilized only to adjust the position of the piston wall 3 and maintain its concentricity with respect to the outer conductor 2.

According to my invention, the actual conductive coupling between the inner end wall or piston 3 and the outer conductor assembly 2 is provided by a plurality of thin flexible conductive straps 6. Each strap is fastened at one end to the outer conductor assembly 2 and at the other end to the piston 3 between the opposing cylindrical surfaces thereof and is substantially longer than the spacing between them. In the completed assembly each strap has a U-shape with the bend or loop extending axially toward the back side of the cavity. The parallel sides of the U-shaped straps are biased by the resilience of the straps against the opposing concentric conductor surfaces, the relative lengths of the sides varying with the piston portions.

To provide a firm conductive support the ends of each strap are preferably both clamped and soldered in place. An end portion 7 of each end of the straps 6 is accordingly bent up 90 degrees and inserted in a slot in the conductive member into which it is to be soldered. One end portion 7 of each strap is positioned in a circumferential groove 8 in the piston 3 around its outer periphery near its end surface defining the resonator end wall and soldered in place. For convenience in soldering, the sides of groove 8 may be peened together to clamp the strap ends tightly.

A groove for the outer ends of the straps is conveniently formed by dividing the outer conductor assembly 2 into two lengthwise sections 9 and 10 with the section 9 defining the front or current carrying portion of the cavity resonator outer wall, and the section 10 defining the back or inactive portion of the resonator assembly. The outer ends 7 of the straps are interleaved between the butted ends of the conductor portions 9 and 10 and preferably soldered in place. One suitable way in which this may be readily accomplished is shown in Fig. 1, where the relative diameters of the ends of the conductor sections 9 and 10 are selected so that section 10 fits into the section 9. The strap ends are preferably positioned against an internal shoulder 11 of section 9 before assembly of the conductor sections 9 and 10 and soldered in place. The external portion 12 of the conductor joint 70 may also be soldered or brazed to increase the strength of the assembly.

The limits of the tuning range available through vary-

ing the axial position of the piston 3 is indicated by Figs. 2a and 2b, the bend or loop of the U-shape strap rolling from near one end of the strap to the other end as the piston is displaced in either direction from the central position of Fig. 1. Fig. 2a represents the low frequency tuning limit as the piston is moved towards the back end of the resonator to increase the cavity size. It will be noted that in this case the inductance of the straps 6 is at a minimum since the area between the cylindrical surfaces of the conductor 2 and piston 3 enclosed by the strap is very small. Fig. 2b shows the high frequency limit as the piston is moved into the cavity to decrease its size. In view of the enlarged area between the strap and the conductor 9, the inductance and hence the voltage therebetween may be large enough to cause arcing in high power installations. Recognizing this limitation, the spacing between the facing conductive surfaces may be decreased to thereby decrease the enclosed area within the loop, and the strap length may also be designed to obtain the desired frequency range without utilizing the full tuning range mechanically possible.

In order to preserve the rolling action of the straps that occurs when the frequency of the resonator is changed, the facing cylindrical portions of the sides of the piston 3 and the conductor section 10 extend for a sufficient distance as guides to permit the sides of the narrow U-shaped straps to lie flat against them to the extent required for any piston position. Binding or permanent bending of the straps is thus avoided, as is essential for long life of the tuning assembly. It should be noted that while the sides of each U-shaped strap lie against the adjacent conductive surfaces no current is conducted therebetween as the only current carried by the straps 6 is along their inner surfaces, i. e., the surfaces facing the interior of the resonator. There is, therefore, no sliding action and no tendency for the straps to become welded in place due to currents conducted by them.

The number and spacing of the resilient straps 6 may be seen in Fig. 3 which represents a cross section view of the resonator of Fig. 1. Each strap is sufficiently narrow so that its width as compared with the degree of arc of the curved conductor portions between which it is fastened is so small as to permit flexing of the strap without binding. The average spacing between adjacent straps is sufficiently small so that the straps in effect produce a solid conductive wall for the transmission of radial currents between the inner and outer conductors. This condition is met when the space between adjacent straps is small as compared to a quarter wavelength at the resonator frequency. The Q of such a resonator is essentially the same as that of a fixed frequency solid wall resonator.

To maintain both long life of the tuning system and ease of tuning, the straps 6 must be both very thin and very flexible. The strap metal accordingly is chosen for its mechanical characteristics. Stainless steel has been found very desirable in this respect, chrome iron also being satisfactory. The surface of each strap facing the interior of the resonator is coated with a thin layer of high conductivity metal, silver or copper being satisfactory. Since at high frequencies the depth of penetration of the current is very slight the coating layer is so thin that it does not affect the mechanical properties of the main body of the strap. I have found a suitable combination for strap construction to be a strap of stainless steel approximately .003 inch thick coated with approximately .0005 inch of copper. Such a strap, despite its heating during the soldering process, will withstand many thousand flexings, the exact number being determined by the thickness of the strap and the radius of the bend.

Fig. 4 is an end view of a rectangular resonator, looking into the tuning end of the resonator. The arrangement is generally similar to that shown in Fig. 1 except that the cross section of the outer conductor 13 is rectangular,

the conductor having top and bottom walls 14 which are longer than the side walls 15. The end wall or piston 16 is also rectangular, each edge of the movable wall 16 being spaced from the facing surface of the outer wall and connected thereto by a flexible strap 17 similarly connected as are the straps 6 of Fig. 1. However, since the facing surfaces of the relatively movable conductor walls are rectilinear the width of the strap is coextensive with the length of the rectilinear surface. Accordingly, only four straps 17 need be employed as compared with the relatively large number of straps necessary between the curved surfaces of Fig. 3. For a simple and common mode of oscillation corresponding to the TE₀₁ mode in a rectangular waveguide, the current flow across the end wall 16 is only in a vertical direction between the longer sides 14 of the rectangular cross section. Accordingly, for such a simple mode, only the top and bottom straps 17 are necessary and the side straps may be eliminated.

Another example of a structure embodying my invention is illustrated in Fig. 5, where a resonator 18 surrounds a portion of the length of the path 19 of an electron stream of a klystron or other electron discharge device. In this case it is desirable to tune the cavity resonator 18 over the desired range while maintaining the resonator vacuum-tight. The cavity resonator 18 is essentially a hollow metal cylinder having annular closures at either end whose central openings permit passage of the electron stream therethrough. Accordingly, as shown in Fig. 5, hollow tubular envelope portions 20 and 21 are respectively hermetically secured to the annular side walls of the resonator. With this type of cavity resonator an entire side wall is not readily movable for tuning the resonator, and instead, a part of one side wall is movable to change the capacitance between the opposite sides. Accordingly, a pair of coaxial hollow cylindrical sections 22 and 23 coaxial with the electron stream extend from opposite side walls toward each other, the spacing between their facing ends determining the capacitance between them and setting the resonator frequency. The position of one of the cylindrical sections 23 is axially adjustable to tune the resonator over the desired range, the tuning cylinder 23 being spaced between concentric inner and outer portions 24 and 25 of one of the end walls of the resonator.

In accordance with my invention the conductive coupling from each of the wall portions 24 and 25 to the tuning member 23 is provided by two concentric arrays of flexible straps 26 and 27 similar to those described in connection with the embodiment illustrated in Fig. 1. The inner circular array of straps 26 is secured with the opposite strap ends conductively fastened between the internal surface of the cylindrical tuning member 23 and the facing surface of the inner wall portion 24. The outer array of straps 27 is similarly connected with one end of each strap fastened to the outer surface of the tuning member 23 and the other end to the inner surface of the outer wall portion 25.

As previously described, each of the flexible straps 26 and 27 is relatively narrow and is positioned to define a U-shaped member opening into the resonator cavity, the opposite sides of each U-shaped strap changing in relative length as the member 23 is axially moved. The single bend or loop of each strap thus rolls along the length of the strap, the strap sides lying against the concentric axially extending surfaces of the moving and stationary members. As also previously described, the ends of each strap may be suitably secured by providing radial grooves in the conductors, the edges of the grooves being peened over after the strap ends are inserted to clamp them while they are being soldered. In order that the assembly may withstand the temperatures required for exhaust of the discharge device of which the resonator is a part a high temperature solder is employed.

While the inner and outer rows of straps 26 and 27 are relatively closely spaced, similarly as are those of

Fig. 3, to provide an effective electrical termination of the cavity and maintain a high Q, additional means are required for a hermetic seal. For this purpose a suitable metallic double bellows 28 is employed, the bellows having concentric inner and outer members hermetically secured at one end to the inner and outer end wall portions 24 and 25. The other ends of the bellows members are hermetically secured to the end of the tuning cylinder 23 extending outside the resonator. Suitable tuning rods 29 are connected to the external end of the tuning cylinder 23 in order that the axial position of the tuning member may be adjusted. A housing member 30 extending between the outer wall portion 25 and the discharge device envelope portion 21 is bored to permit passage of the tuning rods 29 therethrough, thus providing a bearing surface for maintaining the concentricity of the member 23 and avoiding undue stress on the flexible straps.

The high frequency currents, of course, are all contained within the cavity resonator and the housing member 30 plays no part in either the vacuum envelope or the conductive circuit of the resonator. The high frequency currents of the resonator travel on the inner surfaces of the straps 26 and 27 and do not flow through the bellows 28 where the relatively high inductance would be undesirable.

While the present invention has been described by reference to particular embodiments thereof, it will be understood that numerous modifications may be made by those skilled in the art without actually departing from the invention. I, therefore, aim in the appended claims to cover all such equivalent variations as come within the true spirit and scope of the foregoing disclosure.

What I claim as new and desire to secure by Letters Patent of the United States is:

1. An ultra-high frequency apparatus comprising a hollow outer conductor and an inner conductive member coaxial therewith and spaced therefrom, and conductive coupling means therebetween comprising a plurality of flexible straps each having one end secured to the outer conductor and the other end secured to the inner conductor, each of said straps being substantially longer than the spacing between said inner and outer conductors with the central portion thereof flexed in a loop extending in an axial direction to permit axial movement of said conductors with respect to each other.

2. A cavity resonator comprising a hollow outer conductor and an inner conductive member coaxial therewith and spaced therefrom, means for changing the resonator configuration comprising means external of the resonator for maintaining the concentricity of said members when they are moved axially with respect to each other, and conductive means for connecting the opposing surfaces of said outer conductor and said inner conductor at one end of the cavity resonator said conductive means comprising a plurality of flexible metal straps with each strap having its opposite ends secured to the opposing conductor surfaces, said straps being substantially longer than the spacing between said inner and outer conductors with the central portion thereof flexed in a single axially extending loop.

3. An ultra-high frequency resonator comprising an inner and an outer concentric conductor section, means for providing relative axial movement between said sections, and conductive coupling means between said sections comprising a plurality of resilient straps having their opposite ends secured to the facing surfaces of the inner and outer conductor sections, each of said straps being substantially longer than the spacing between said inner and outer conductors with the central portion thereof flexed in a single loop extending in an axial direction

away from the interior of the resonator, the respective sides of the loop so formed lying against said facing conductor surfaces.

4. An ultra-high frequency resonator comprising an inner and an outer concentric conductor section, means for providing relative axial movement between said sections, and conductive coupling means between said sections comprising a plurality of resilient metal straps having their opposite ends fixed to the facing surfaces of the inner and outer conductor sections, each of said straps being substantially longer than the spacing between said inner and outer conductors with the central portion thereof flexed in a single loop extending in an axial direction away from the interior of the resonator and the respective sides of the loop biased against said facing conductor surfaces, the spacing between adjacent straps being relatively small with respect to one quarter wavelength at the resonator frequency.

5. An ultra-high frequency resonator comprising an inner and an outer concentric conductor section, means for providing relative axial movement between said sections, and conductive coupling means between said sections comprising a plurality of resilient straps each being substantially longer than the spacing between said inner and outer conductors and having its opposite ends secured to the facing surfaces of the inner and outer conductor sections with the central portion thereof flexed in a single loop extending in an axial direction, each loop having a highly conductive concave surface facing the interior of the resonator.

6. An ultra-high frequency resonator comprising an inner and an outer concentric conductor section, means for providing relative axial movement between said sections, and conductive coupling means between said sections comprising a plurality of resilient straps having a highly conductive coating thereon, each of said straps being substantially longer than the spacing between said inner and outer conductors and having its opposite ends fixed to the facing surfaces of the inner and outer conductor sections with the central portion thereof flexed in a single loop extending in an axial direction away from the interior of the resonator with the conductive coating facing the resonator interior, the spacing between adjacent straps being small with respect to one quarter wavelength at the resonator frequency.

7. An ultra-high frequency resonator comprising an inner and outer concentric conductor section having current facing surfaces, means for providing relative axial movement between said sections, conductive coupling means connected between said sections comprising a plurality of narrow resilient straps having a highly conductive coating thereon facing the interior of the resonator, each of said straps being substantially longer than the spacing between said inner and outer conductors and having its opposite end portions lying against said facing surfaces with the central portion thereof flexed in a single loop extending in an axial direction away from the interior of the cavity.
